TAXICAB CALL SYSTEM

Bernard D. Willis, Oak Park, Ill., assignor to
 Associated Electric Laboratories, Inc., Chicago,
 Ill., a corporation of Delaware

Application October 18, 1940, Serial No. 361,675

21 Claims.

(Cl. 179—2)

The present invention relates to signaling systems, and more particularly to improvements in signaling systems designed for use in regulating the movement of public service vehicles such as taxicabs.

As explained in Patent No. 2,023,225, granted December 3, 1935, Bernard D. Willis and Harvey L. Harris, a factor contributing largely to confusion of traffic in metropolitan areas resides in the almost continuous "cruising" or idle movement of public taxicabs, the drivers of which are scouting for passengers or fares. In this patent there is disclosed a system for governing the movement of cabs in such a manner that the cabs are under complete control of a centrally located supervisory point or cab stand from which the cabs may be dispatched to various calling stations in response to cab call signals transmitted to the supervisory point. In the disclosed arrangement, the call stations are connected to signaling circuits or lines extending to the control or master station located at the supervisory point, and call buttons are provided for transmitting the call signals over the lines to the control station. An electromagnetically controlled mechanical lockout arrangement is utilized for limiting the system to the handling of one call at a time.

It is an object of the present invention to provide an improved system of the character described, which is so arranged that the call signals are transmitted to the cab stands from which cabs may be dispatched to the calling points with a minimum of traffic confusion.

It is another object of the invention to provide an improved cab call system of the character described, which is so arranged that the cab call signals are transmitted to cab stands from which cabs may proceed to the calling points over routes requiring a minimum number of traffic turns of the same type.

It is a further object of the invention to provide, in a system of the character described, an improved and exceedingly simple lockout arrangement, entirely electrical in character, for preventing any signaling line from being occupied with more than one call at any given time.

It is still another object of the invention to provide, in a system of the character described, an improved arrangement for signaling a calling party as to the idle or busy condition of a line upon which a call is initiated, and for enabling the calling party to determine when the line becomes idle.

It is a still further object of the invention to provide a signaling system of the character described, which is simple to operate, requires a minimum amount of equipment, and is positive and reliable in the performance of its intended functions.

The invention is illustrated in its embodiment in the business district of a metropolitan area which includes both one and two-way streets arranged to form the conventional grid type of street pattern. The call signals are disposed along opposite sides of each street, and the cab stands, of which there are two, are located at oppositely disposed corners of the congested traffic area so that they are disposed on opposite sides of the two-way streets at points therealong where the traffic congestion starts. Each cab stand is equipped with a control or dispatcher station from which the signaling circuits or lines are fanned out to the various call stations. In accordance with the present invention, the call stations located along one side of each two-way street are served by signaling circuits which extend to the control station at one of the cab stands, while the call stations located along the opposite side of each two-way street are connected to signaling circuits which extend to the control stations provided at the other of the cab stands. By virtue of this arrangement, cabs dispatched to various calling points are required to make the least confusing type of traffic turn, namely, right-hand turns. In further development of this concept, the call stations disposed along opposite sides of each one-way street are connected to signaling circuits which extend to the control station at the same cab stand, the particular control station being determined by the assigned direction of traffic flow over the particular street, whereby cabs summoned to the call station disposed along the one-way streets are required to make only right-hand turns in entering such streets.

In the physical embodiment of the system, each signaling circuit or line extends from the master station to a plurality of call stations. The master station is equipped with a signal control relay for indicating the presence of a call on each line, and each of the call stations is provided with a call relay and a switch for connecting the associated call relay in series with the signal control relay connected with the line at the master station. The release of any operated call relay is under the control of means provided at the master station for establishing a low resistance shunt across the operated call relay to cause the de-

energization thereof. Provisions are also made whereby not more than one of the call relays can be operated at any one time. In one embodiment of the physical arrangement, each call station is equipped with a transmitter and receiver, whereby exact information may be dispatched to the control station as to the location of a calling party. In order to permit a calling party to determine when a busy line becomes idle, an arrangement is provided whereby the calling party may listen in on a line without being able to transmit speech currents thereover. An additional signal is provided at each call station for indicating to a calling party that the line connected to the call station is idle.

The novel features believed to be characteristic of the invention are set forth with particularity in the appended claims. The invention, both as to its organization and method of operation, together with further objects and advantages thereof, will best be understood by reference to the specification taken in connection with the accompanying drawings in which Figure 1 illustrates the application of the system to a congested traffic area, wherein the streets are arranged to form the well-known grid type of pattern, and Fig. 2 illustrates the circuit arrangement of a portion of the system shown in Fig. 1.

Referring now more particularly to Fig. 1 of the drawings, the street pattern there illustrated is typical of the thoroughfare arrangement provided to serve the main business district of a large city. The thoroughfares include a one-way First Street for the use of traffic proceeding in a westward direction, a one-way Second Street for the use of traffic proceeding in an eastward direction, two-way Main and Broadway Streets for accommodating traffic proceeding in both the eastward and westward directions, and A, B and C Avenues intersecting at right angles the various enumerated streets. As illustrated in the drawings, these streets are arranged to serve twenty-four business blocks. The taxicab traffic along the various streets of this business area is limited to cabs proceeding from either of the two cab stands 10 and 11 to specified destinations along one of the streets, for the purpose of picking up passengers, to cabs proceeding from loading points to passenger designated unloading points, and to cabs proceeding from distant loading points to passenger designated unloading points in the area. The summoning of cabs from the two cab stands 10 and 11 to pickup points at which passengers are located is accomplished through the provision of two signaling networks individual to the two cab stands. To this end, each street is provided with call stations S1, S2, C3, S4, S5, etc., located at convenient points along the two sides thereof. These call stations, which may be located in store and hotel entrances, for example, at spaced intervals along the streets, are connected to signaling lines or circuits which extend to control stations provided at the cab stands 10 and 11, respectively. Preferably, the call stations are so located that a person desiring a cab does not have to cross a street or walk more than one half of a block to reach a call station. More specifically, the call stations most conveniently located for traffic stops by vehicles proceeding in a westward direction are connected to signaling circuits which terminate at the control station provided at the cab stand 10, whereas the call stations most conveniently located for traffic stops by vehicles proceeding in an eastward direction are connected

70 75

to signaling circuits terminating at the control station provided at the cab stand 11. Thus, the call stations S1 to S10, inclusive, are connected to the lines 1, 2 and 3, all of which terminate at the control station located at the cab stand 10, while the call stations S20 to S25, inclusive, are all connected to the line 7 which extends to the control station provided at the cab stand 11. In this regard it will be noted that the cab stands 10 and 11 are respectively located at the northeast and southwest corners of the congested traffic area, so that a cab dispatched from the cab stand 10 may enter any one of the east-west streets at the point therealong where traffic congestion begins by making a right turn. With the system arrangement described above, it will be noted that if a call is initiated at the call station S6, for example, at a time when the lines 1 to 5, inclusive, are idle, a signaling connection is set up between this station and the control station provided at the cab stand 10, whereby the dispatcher at this cab stand is informed that a passenger located at the station S6 desires transportation. A cab dispatched from this stand to pick up the waiting passenger may enter Main Street at the east side of the congested area by making a right turn, and is on the proper side of the street for picking up the passengers located at the calling station S6. Similarly, if a fare located at the station S23 signals the dispatcher at the cab stand 11 that a cab is desired, the dispatched cab may enter Main Street at the west side of the congested area by making one right turn, and is on the proper side of the street for making a stop at the calling station S23. On the other hand, if the fare is located at the station S26 disposed on the west side of B Avenue between Main and Broadway Streets, the cab dispatched from the cab stand 11 may proceed to the loading point by making two right-hand turns, and is on the proper side of the street for making a stop at the calling station. The call stations located along opposite sides of each one-way street are necessarily served by signaling circuits extending to the control station at the same cab stand. Thus, the call stations provided along First Street are most conveniently served by the cab stand 10 and, accordingly, these stations are all connected to lines terminating at the control station provided at this stand. Similarly, the call stations provided along Second Street are most conveniently served by cabs dispatched from the cab stand 11 and, accordingly, all of these call stations are connected to signaling circuits terminating at the control station provided at the cab stand 11. The call stations along the intersecting avenues are, for the most part, connected to signaling circuits which extend to the control station provided at the cab stand from which cabs may be dispatched to the call stations by making a minimum number of right turns, thus eliminating traffic confusion. In this regard it will be noted that for a cab to proceed from the cab stand 10 to the call station S26 by making only right turns, four such turns would be required, whereas a cab proceeding to this station from the cab stand 11 can reach its destination by making only two right turns.

The individual signaling circuits or lines, as terminated at the control stations respectively provided at the two cab stands, serve partially to indicate to the dispatcher the location of call stations at which calls are initiated. This is accomplished by the particular circuit arrange-

ment of the equipment illustrated in Fig. 2 of the drawings. As there illustrated, the equipment provided at the master station 10A located at the cab stand 10 comprises a line finder 111 at which are terminated all of the signaling circuits or lines extending to the call stations individually served by the cab stand 10. This line finder is of the well-known rotary type, comprising four sets of contacts, each including twenty-five contact points, wipers 112 to 115, inclusive, individually associated with the contact sets, and a motor magnet 119 for driving the enumerated wipers over the contacts of their associated contact sets. The wiper carrying shaft of the switch 111 is also equipped with a pointer 117 arranged to cooperate with an indice bearing index plate 118 to identify the line or signaling circuit selected through each operation of the finder.

The signaling equipment provided at the master station 10A includes a telephone instrument, preferably of the well-known handset type, having embodied therein a transmitter 121 and a receiver 122 arranged to be supported upon a cradle which is provided with a plunger operated cradle switch including the contacts 125 and 126. More specifically, the cradle switch is so arranged that, with the handset supported by the cradle, the contacts 125 and 126 are respectively disengaged, and when the handset is removed from the cradle, these contacts are respectively operated into engagement. The transmitter 121 and receiver 122 are interconnected with the windings of an induction coil 123, a condenser 124 and the line wipers 113 and 115 of the finder switch 111. For the purpose of supplying energizing current to the transmitter 121 and the various control relays and signals illustrated in the drawings, there is provided a source of direct current, not shown, but having its positive terminal connected to the various ground points illustrated in the drawings, and its negative terminal connected to a negative bus at which the various negative circuit terminals are commonly terminated. Current from this source is delivered to the transmitter 121 over paths including the voice current choke coils 127 and 128, a low impedance condenser 129 being provided to pass voice current through the lower winding of the induction coil 123 in preference to the choke coils 127 and 128 and the current source. The line equipment provided at the master station includes signal control relays 140, 150, etc., which are individually associated with the lines 1, 25, etc., terminating in the bank contacts of the finder switch 111. The common relay equipment comprises a finder stop relay 160 and a pair of additional relays 170 and 180, which function to control the release of calling signaling circuits, the operation of a call meter 131 and the operation of an audible signal device 130. The signal equipment provided at the master station 10A also includes signal lamps 145, 155, etc., individual to the lines 1, 25, etc., and a common call signal lamp 132.

The equipment provided at the call stations connected to each line may take either of two forms, depending upon whether voice communication between the call stations and the master station is required. Thus, the equipment provided at the call stations S1 and S2 served by the line 1 includes provisions for voice communication over this line, whereas the facilities provided at the call station S99 only include provisions for transmitting a calling signal over the line 25 to the master station 10A. More specifically, the equipment provided at the call station S1 com-

prises a transmitter 205 and a receiver 206 arranged to be serially bridged across the conductors of the line 1 through operation of a call relay 200. Preferably, the bridging contacts 201 of the relay 200 are shunted by a condenser 208, as indicated in dash lines, whereby a party using the station S1 may listen in on the line 1 without being able to transmit signal currents thereover. The energization of the call relay 200 is under the control of a call switch 204 which is of the non-locking push button type. Preferably, the call relay 200 is equipped with a target 207 arranged to be pivoted into a position behind the window 209 of the control panel provided at the station S1 in response to energization of the relay 200, thereby to produce a signal that the line 1 is idle. The call relays provided at the other call stations are similarly equipped. The call station S2 is similar in arrangement to the station S1 in that it includes a call relay 210, a call switch 214, a transmitter 215 and a receiver 216. The equipment provided at the call station S99, on the other hand, is somewhat more simple in character, since voice communicating facilities are not provided at this station. Thus, the call station S99 includes only a call relay 220 and a call switch 224. In connection with the lines arranged to provide signaling facilities only, it is desirable to equip these lines with additional line identification signaling apparatus in order to enable the control station attendant to distinguish between the two types of lines. To this end there is provided in association with the line 25 a distinctive signal current source, the voltage of which is impressed upon the line 25 through a transformer 156 and a condenser 157. This voltage may be interrupted in accordance with a predetermined code arbitrarily assigned to the line 25 by means of any well-known type of code interrupter, and may be either continuously applied to the line 25 over a path including the strap 158 or may be applied to the line 25 only when a call exists on this line by extending the voltage application path through the make contacts 152 of the signal control relay 150.

In the operation of the signaling network illustrated in Fig. 2 of the drawings, if a party desires to summon a cab to the call station S1, the push button call switch 204 is momentarily operated to complete a circuit for energizing the call relay 200 in series with the signal control relay 140 individual to the line 1. This circuit extends from ground by way of the lower winding of the relay 140, the line conductor 1b, the two windings of the relay 200 in series, the contacts of the switch 204, the line conductor 1a and the upper winding of the relay 140 to the negative terminal of the current source. When thus energized, the relay 200 operates to bridge its low resistance upper winding across the conductors of the line 1 over a path including the contacts 202 and 203. Thus, a holding circuit is established for the relay 200 from which the high resistance lower winding of this relay is excluded and, as a result, the voltage drop between the conductors 1a and 1b of the line 1 is reduced by an amount such that the call relay 210, for example, will not operate if the call switch 214 is operated prior to the release of the call relay 200. Thus, all of the call stations served by the line 1 are prevented from gaining access to this line until the call relay 200 provided at the calling station S1 is released. In operating, the relay 200 also completes, at its contacts 201, a path for bridging the

series connected transmitter 205 and receiver 206 across the conductors of the line 1. In addition, the relay 200 operates to rotate the target 207 in a clockwise direction, thereby to position this target behind the window 209 of the control panel in order to indicate to the party initiating the call that the line 1 is idle and the call has been transmitted to the master station.

The signal control relay 140 operates when energized in series with the windings of the call relay 200. At its contacts 141, the relay 140 completes or prepares a circuit for energizing the signal lamp 145 individual to the line 1, this circuit being completed only in the event the wipers of the finder switch 111 are standing in engagement with the contacts terminating the conductors of the line 1. More specifically, this circuit extends from ground by way of the wiper 114 and its associated first contact, the contacts 141 and the filament of the lamp 145 to the negative terminal of the current source. At its contacts 142, the relay 140 prepares or completes a circuit for energizing the stop relay 160, this circuit extending from ground by way of the contacts 142, the wiper 112 and its associated first contact, and the winding of the relay 160 to the negative terminal of the current source, and only being completed in the event the wipers of the finder switch 111 engage their respective associated first contacts. Assuming that the wipers of the line finder 111 occupy this position, the relay 160 operates to open its contacts 161 and thus prevent operation of the motor magnet 119. If, on the other hand, the wipers of the finder switch 111 do not engage their respective associated first contacts at the time the call is initiated at the station S1, the relay 140, upon operating, completes, at its contacts 143, a circuit including the contacts 161 for energizing the motor magnet 119 in parallel with the filament of the common call signal lamp 132. When thus energized, the magnet 119 operates to complete, at its contacts 120, an obvious alternative operating circuit for the relay 160. The relay 160 now operates to open, at its contacts 161, the path normally short-circuiting the resistor 162, and thus reduce the energization of the magnet 119 sufficiently to cause the release thereof. When released in this manner, the spring biased pawl and ratchet mechanism of the finder switch 111 operates to advance the wipers 112 to 115, inclusive, one step. The magnet 119, in restoring, also opens its contacts 120 to interrupt the operating circuit for the relay 160, causing this relay to restore and recomplete the operating circuit for the magnet 119. The interrelated operation of the magnet 119 and the relay 160 continues until the wipers of the finder switch 111 are positioned in engagement with their respective associated first contacts, at which time the relay 160 is energized over the above-traced circuit extending to ground through the make contacts 142. When this circuit is completed, the relay 160 remains in its operated position to prevent further operation of the magnet 119, with the result that further stepping of the wipers 112 to 115, inclusive, is prevented. In addition, the enumerated wipers, upon engaging their associated first contacts, connect the conductors of the line 1 to the substation equipment provided at the master station 10A, and complete the above-traced circuit for energizing the line identification lamp 145. Further, the pointer 117 is positioned opposite the index designating the line 1 to give an indication to the dispatcher

that the line 1 is calling. From a consideration of the signaling arrangement, it will be observed that the lamp 132, when energized, indicates that one of the lines of the system has a call thereon, but does not indicate which line is calling. The lamp 145, on the other hand, when illuminated indicates that the line 1 is calling, and this signal is supplemented by the indication given by the pointer 117 cooperating with the index plate 118. A further audible signal is produced through operation of the buzzer 130, this buzzer being energized over a circuit including the contacts 143 and 174 in response to operation of the relay 140.

5 The dispatcher, upon receiving these signals, may remove the handset from its supporting cradle for the purpose of answering the call. In response to this operation, the cradle switch is operated to move the switch springs 125 and 126, 10 respectively, into engagement. At the springs 125, a circuit including the choke coils 127 and 128 is completed for delivering energizing current to the transmitter 121. At the springs 126, an obvious circuit is completed for energizing the relay 170. The relay 170, upon operating, closes its contacts 172, to complete an obvious circuit for energizing the slow-to-release relay 180. At its contacts 171, the relay 170 opens a point in the low resistance bridging path which is subsequently established across the conductors of the line 1 in order to cause the release of the operated call relay 200. At its contacts 173, the relay 170 completes an obvious circuit for energizing the call meter 131, whereby the call is registered. At its contacts 174, the relay 170 15 interrupts the operating circuit for the buzzer 130, thus terminating the audible signal indication. The relay 180 operates shortly following the operation of the relay 170, and closes its contacts 181 to prepare the low resistance bridge across the conductors of the line 1. At its contacts 182, the relay 180 opens the operating circuit for the call meter 131. Following the operations just described, a two-way communication 20 connection is established between the master station 10A and the call station S1, this connection including the two sides of the line 1. In this regard it will be noted that current for energizing the transmitter 205 provided at the call station S1 is supplied to this transmitter over the line conductors 1a and 1b through the windings of the signal control relay 140. With this communication connection established, the calling party may inform the dispatcher as to the number of the call station, thus identifying its location. After the call is disposed of in this manner, the equipment may be released under the control of the dispatcher. More specifically, when the handset provided at the master station 10A is replaced upon its supporting cradle, the cradle switch is operated to cause the disengagement of the contacts 125 and 126, respectively. As a consequence, the current supply circuit to the transmitter 121 is broken and the relays 170 and 180 are caused sequentially to restore. During the period which elapses between the release of the relay 170 and the release of the relay 180, the low resistance bridge referred to above is completed between the conductors 1a and 1b of the line 1, this bridge including the operated make contacts 181 and the restored break contacts 171. With this path completed, the low resistance holding winding of the operated call relay 200 25 is effectively short-circuited, causing this call re-

lay to restore. When the relay 180 restores, shortly following the release of the call relay 200, the bridging path across the conductors of the line 1 is interrupted to cause the deenergization and release of the signal control relay 140. The relay 140, upon restoring, opens its contacts 141 and 143 to deenergize the signal lamps 145 and 132. At its contacts 143, the relay 140 also opens a point in the operating circuits for the buzzer 130 and the motor magnet 119. At its contacts 142, the relay 140 interrupts the above-traced circuit for energizing the stop relay 160. Following the release of the relay 160, the equipment is fully restored to normal in readiness to handle another call.

As indicated above, the arrangement of the signaling network is such that each line may handle only one call at a time. Thus, if the call relay 210, provided at the station S2, is operated at the time the above-described call is initiated at the station S1, the voltage difference between the conductors 1a and 1b of the line 1 is insufficient to cause the operation of the call relay 200 provided at the calling station S1. The calling party, by observing that the target 207 is not moved to a position behind the window 209, is informed that the line 1 is in use. Assuming that the condenser 208 is employed in the circuit provided at the call station S1, the calling party may, by listening in on the line 1, determine when the line is released by the dispatcher at the master station 10A and thus ascertain without undue delay when to again initiate the call. It will be observed that with the transmitter 205 and the receiver 206 only reactively coupled to the line 1, energizing current is not supplied to the transmitter 205, and, accordingly, the party using the call station S1 cannot break in upon the conversation being held between the call station S2 and the master station 10A.

The arrangement of the system is such that the initiation of a call on one of the signaling lines does not preclude the later initiation of a call on another of the lines before the first call is released, although the later initiated call will be extended to the master station by the line finder 111 only after the first call is disposed of. Thus, if the master station equipment is occupied with a call originating on the line 1, for example, such that the relays 140, 160, 170 and 180 are operated and a call is initiated at the call station S99, for example, through operation of the switch 224, the call relay 220 is energized and locks up in series with the signal control relay 150. Due to the energized condition of the relay 160, however, the finder switch 111 is prevented from operating to seize the calling line 25. The two relays 220 and 150 remain operated during the release of the master station control equipment and the operated relays associated with the line 1. Immediately the relay 160 restores to terminate this release operation, the circuit for energizing the motor magnet 119 is recompleted, whereby operation of the finder switch 111 is initiated to seize the line 25 upon which the call is waiting. The manner in which the second call, namely, that present on the line 25, is extended to the master station 10A, and the equipment is released under the control of the dispatcher attending this station, is exactly the same as described above and will readily be apparent from the foregoing explanation. In this case, however, it will be noted that when the wipers of the finder switch 111 are positioned

to engage the contacts terminating the conductors of the line 25, the characteristic signal voltage identifying the line 25 is transmitted to the receiver 122 to indicate to the dispatcher that the line 25 is calling, thus supplementing the visual signals given by the lamp 155 and the indicating mechanism of the finder switch. More specifically, the path traversed by this signal current extends from the ungrounded terminal of the secondary winding of the transformer 156 by way of the condenser 157, the contacts 152, the wiper 115 and its associated twenty-fifth contact, the receiver 122, the upper winding of the induction coil 123, the condenser 124, the wiper 113 and its associated twenty-fifth contact, and through the lower winding of the relay 150 to ground. The coded signals produced by the receiver 122 in response to the signal current traversing this path positively identifies the calling line to the dispatcher. If desired, the make contacts 152 included in this path may be omitted, the upper terminal of the condenser 158 being connected directly to the upper conductor of the line 25 by means of a strap 158.

From the above explanation, it will be apparent that successively initiated calls on the various signaling lines are handled in a predetermined order in accordance with the termination of these lines in the bank contacts of the line finder 111 and that, as each communication or signalling connection is released, the next line in order having a call present thereon is connected with the master station. By virtue of this arrangement, the call stations associated with any one line are prevented from monopolizing the call answer facilities of the master station 10A to the exclusion of other lines.

While there has been described what is at present considered to be the preferred embodiment of the invention, it will be understood that various modifications may be made therein, and it is contemplated to cover in the appended claims all such modifications as fall within the true spirit and scope of the invention.

45. What is claimed is:

1. In a telephone system, a line, a plurality of call stations associated with said line, each of said stations including a transmitter and a receiver and a call relay operative to connect the associated transmitter and receiver to said line, means provided at one of said call stations for rendering the receiver at said one station operative to reproduce signal currents transmitted over said line when the associated control relay is released, and a master station including signal control means operative in response to operation of any one of said relays.

2. In a telephone system, a line, a plurality of call stations associated with said line, each of said stations including a transmitter and a receiver and a call relay operative to connect the associated transmitter and receiver to said line, the receiver provided at at least one of said call stations being reactively coupled to said line to respond to signal currents transmitted thereover regardless of the position of the associated call relay, and a master station including signal control means operative in response to operation of any one of said relays.

3. In a signaling system, a line, a plurality of call stations associated with said line, a master station including a signal control relay, each of said stations including a call relay, means at each call station for connecting the associated call relay in series with said control relay, and

means at said master station for establishing a low resistance shunt across any operated call relay in order to cause the release thereof.

4. In a signaling system, a line, a plurality of call stations associated with said line, a master station including a signal control relay, each of said stations including a call relay, means at each call station for connecting the associated call relay in series with said control relay, a receiver at said master station connected to respond to signals transmitted over said line from said call stations, a support for said receiver, and means operative in response to replacement of said receiver upon said support for establishing a low resistance shunt across any operated call relay in order to cause the release thereof.

5. In a signaling system, a line, a plurality of call stations associated with said line, a master station including a signal control relay, each of said call stations including a call relay operative to complete an operating circuit for said signal control relay, and means at said master station for establishing a low resistance shunt across any operated call relay in order to cause the release thereof.

6. In a signaling system, a line, a plurality of call stations associated with said line, a master station including signal control means, each of said call stations including a call relay operative to cause the operation of said signal control means, and means at said master station for establishing a low resistance shunt across any operated call relay in order to cause the release thereof.

7. In a signaling system, a line, a plurality of call stations associated with said line, a master station including signal control means, each of said call stations including a call relay operative to cause the operation of said signal control means, electric circuit means interconnecting said relays to prevent the concurrent operation of more than one of said relays, and means at said master station for establishing a low resistance shunt across any operated call relay in order to cause the release thereof.

8. In a signaling system, a line, a plurality of call stations associated with said line, a master station including signal control means, a receiver at said master station connected to respond to signals transmitted over said line, a support for said receiver, each of said call stations including a call relay operative to cause the operation of said signal control means, and means operative in response to replacement of said receiver upon said support for establishing a low resistance shunt across any operated call relay in order to cause the release thereof.

9. In a signaling system, a line, a plurality of call stations associated with said line, a master station including signal control means, a receiver at said master station connected to respond to signals transmitted over said line, a support for said receiver, each of said call stations including a call relay operative to cause the operation of said signal control means, and means operative in response to replacement of said receiver upon said support for causing the release of any operated call relay.

10. In a signaling system, a line, a plurality of call stations associated with said line, a master station including signal control means, a receiver at said master station connected to respond to signals transmitted over said line, a support for said receiver, each of said call stations including a call relay operative to cause the

operation of said signal control means, electric circuit means interconnecting said relays to prevent the concurrent operation of more than one of said relays, and means operative in response to replacement of said receiver upon said support for causing the release of any operated call relay.

11. In a signaling system, a line, a plurality of call stations associated with said line, a source of current, a master station including a signal control relay having windings bridged across the conductor of said line in series with said current source, each of said call stations including a call relay and a switch for bridging the windings of the associated call relay across the conductors of said line for energization in series with the windings of said control relay, and means responsive to the operation of one of said call relays for establishing a low resistance shunt across the windings of the other call relays in order to prevent the operation thereof.

12. In a signaling system, a line, a plurality of call stations associated with said line, a source of current, a master station including a signal control relay having windings bridged across the conductors of said line in series with said current source, each of said call stations including a call relay and a switch for bridging the windings of the associated call relay across the conductors of said line for energization in series with the windings of said control relay, and means at said master station for establishing a low resistance bridge across the conductors of said line in order to cause the release of any operated one of said call relays.

13. In a signaling system, a line, a plurality of call stations, associated with said line, a source of current, a master station including a signal control relay having windings bridged across the conductors of said line in series with said current source, each of said call stations including a call relay and a switch for bridging the windings of the associated call relay across the conductors of said line for energization in series with the windings of said control relay, means at said master station for establishing a low resistance bridge across the conductors of said line in order to cause the release of any operated one of said call relays, and means responsive to the operation of one of said call relays for establishing a low resistance shunt across the windings of the other call relays in order to prevent the operation thereof.

14. In a signaling system, a line, a plurality of call stations associated with said line, a source of current, a master station including a signal control relay having windings bridged across the conductors of said line in series with said current source, each of said call stations including a call relay having a high resistance operating winding and a low resistance holding winding, a switch at each of said call stations for connecting the windings of the associated call relay across the conductors of said line to cause the energization of the associated call relay in series with said signal control relay, and means responsive to the operation of any one of said call relays for short-circuiting the operating winding of the operated call relay, thereby to establish a low resistance bridge across the conductors of said line which prevents operation of the other call relays.

15. In a signaling system, a line, a plurality of call stations associated with said line, a source of current, a master station including a signal

control relay having windings bridged across the conductors of said line in series with said current source, each of said call stations including a call relay having a high resistance operating winding and a low resistance holding winding, a switch at each of said call stations for connecting the windings of the associated call relay across the conductors of said line to cause the energization of the associated call relay in series with said signal control relay, means responsive to the operation of any one of said call relays for short-circuiting the operating winding of the operated call relay, thereby to establish a low resistance bridge across the conductors of said line which prevents operation of the other call relays, means also responsive to the operation of said one call relay for bridging the holding winding of said one call relay across the conductors of said line independently of its associated switch, and means at said station for short-circuiting the holding winding of said one call relay over a path including the conductors of said line, thereby to cause the release of said one call relay.

16. In a signaling system, a line, a plurality of call stations associated with said line, a master station including signal control means, each of said call stations including a call relay operative to cause the operation of said signal control means, means for preventing the operation of more than one of said relays, and a signal device at each of said call stations controlled by the associated call relay.

17. In a signaling system, a line, a plurality of call stations associated with said line, a master station including signal control means, each of said call stations including a call relay operative to cause the operation of said signal control means, means for preventing the operation of more than one of said relays at a time, and means comprising signal devices individually controlled by said relays for indicating to call station users the idle or busy condition of said line.

18. In a signaling system, a line, a plurality of call stations associated with said line, a master station including signal control means, a receiver at said master station connected to respond to signals transmitted over said line, a support for said receiver, each of said call stations including a call relay operative to cause the operation of said signal control means, a call meter, and means operative in response to removal of said receiver from said support for causing the operation of said meter and in response to replacement of

said receiver upon said support to cause the release of any operated call relay.

19. In a signaling system, a line, a plurality of call stations associated with said line, a master station including signal control means, a receiver at said master station connected to respond to signals transmitted over said line, a support for said receiver, each of said call stations including a call relay operative to cause the operation of said signal control means, a call meter, a pair of relays sequentially operative in a predetermined order in response to removal of said receiver from said support and sequentially released in the same order in response to replacement of said receiver upon said support, means responsive to the operation of said pair of relays for causing the operation of said meter, and means operative in response to the release of said pair of relays for establishing a low resistance shunt across any operated call relay in order to cause the release thereof.

20. A public service system for a plurality of streets including at least one two-way street, said system comprising call signals spaced along said two-way street upon opposite sides thereof, a pair of control stations respectively located on opposite sides of said two-way street, a signal circuit connecting the call stations located along one side of said two-way street with one of said control stations, and another signaling circuit connecting the call stations located along the opposite side of said two-way street with the other of said control stations.

21. A cab call system for a plurality of streets including at least one two-way street and a one-way street extending substantially parallel with said two-way street, said system comprising call signals spaced along said one and two-way streets upon opposite sides thereof, cab stands respectively located on opposite sides of said two-way street, control stations at said cab stands, a signaling circuit connecting the call stations located along one side of said two-way street with the control station at one of said cab stands, a second signaling circuit connecting the call stations located along the opposite side of said two-way street with the control station at the other of said cab stands, and a third signaling circuit connecting the call stations located along at least one side of said one-way street with the control station at a predetermined one of said cab stands.

BERNARD D. WILLIS.
